UNITED STATES PATENT OFFICE

KINGSLEY L. MARTIN, OF MONTCLAIR, NEW JERSEY, ASSIGNOR OF ONE-HALF TO
A. C. DANKS, OF CLEVELAND, OHIO

WATER-TUBE BOILER

Application filed February 20, 1928. Serial No. 255,558.

This invention relates to water tube boiler construction and particularly to the vertical bent tube types known as Stirling, Connelly, and others. The best known of these employ a bottom drum and three spaced upper drums with a set of tubes extending from the bottom drum to each upper drum but in some cases there are only two upper drums and two banks of tubes. The invention has to do primarily with the protection of the upper and lower drums from destructive action by the gases of combustion and secondarily to improve the operating efficiency of the boilers by preventing the accumulation of soot and dust in the gas passageways, principally on top of the lower drum by a novel arrangement of refractory baffles in the boiler.

First as regards the protection of the lower drum. It has been customary to use baffles in or on the first bank of tubes parallel to their length so that soot, ashes and dust deposit in the angle formed by the baffle and upper surface of the drum and in contact therewith. This accumulation contains chemical agents which attack the metal in the tubes and drum and gradually corrodes them to such an extent that their replacement is necessary. Owing to the inconvenient location of the parts attacked, inspection is difficult and a dangerous condition may develop apart from the expensive nature of repairs. This action is prevented by my invention, which provides for a novel construction of the lower end of the front baffle by which the baffle instead of being continued along the tubes of the first bank is constructed transversely across said tubes in a downwardly sloping direction across the space between the first and second bank of tubes and partly or wholly across the second and third bank of tubes and passing over the lower drum. By this means a smooth sloping shelf is provided on which, due to the scouring action of the gases at this point, acting on the smooth inclined surface, only a small portion of the solid matter entrained in the gases will deposit, the balance being carried over behind the lower drum and dropped out of suspension by the expanding gases as their velocity is reduced. The solid matter will then fall into

soot chambers ordinarily provided behind the lower drum whence it is readily removed at convenient intervals.

The removal of such solid matter, as does deposit on the upper surface of the sloping baffle, may be effected by the ordinary type of steam soot blowers or by hand lances, but pending such removal, the material is held out of contact with the junction of the tubes and drum where its corrosive action is greatest. The prevention of the dust accumulation also avoids an increase in draft loss through the boiler due to obstruction of the gas passage and maintains the thermal efficiency by preventing the covering of part of the heat absorbing surface by dust having high insulating qualities.

Provision is also made against overheating the rear upper drum. In this type of boiler, the rear drum at low capacity operation is approximately half full of water, the upper half being filled with steam, but when operating at high capacities, the water level is lowered, and may sink into the upper part of the rear bank of tubes leaving the drum full of steam only. As the type of cross baffleing preferably used, brings gases at high temperature in contact with the drum, it is necessary to protect the drum particularly the joint or splice between the upper and lower halves of the drum. This splice must also be left uncovered for inspection. It is also desirable to protect the junction of the upper end of the rear bank of tubes with the drum. Such upper drum protection, as has heretofore been provided consists of loose refractory tile laid on some of the steam generating tubes of the boiler or on water circulating tubes between the drums. These loose tile are necessarily not gas or dust tight, and where pulverized coal is used as fuel, unburned fuel may penetrate the baffle and become an element of danger from explosion. I have, therefore, provided a construction applicable to practically all types of boilers of this kind now in use, wherein a baffle is placed between the middle and rear drums starting from approximately the point where the rear tube of the middle bank of tubes enters the middle drum and extending rearwardly

either horizontally or inclined downwardly until it meets the front surface of the rear drum at some point below the drum splice and thence following the outer lower surface 5 of the drum through and around the upper ends of the tubes in the rear bank to a junction with the rear baffle wall which extends downwardly from the drum. A downwardly inclined baffle between the drums is preferred 10 where the tube arrangement permits, as facilitating the change of direction of the gas flow below it at this point, and preventing the formation of eddy currents. The baffle consists of plastic refractory material, reinforced 15 with rods or shapes embodied in the material, so as to be protected from the hot gases, forming an absolutely gas and dust proof baffle. The portion of the baffle between the drums is preferably supported by hanger rods from 20 the steam circulating tubes, but may be self supported or supported by structural steel members suitably placed. The portion of the baffle around the tubes is supported in part by friction on the tubes and in part by reinforcing rods extending from back to front. 25 Boilers of this type ordinarily have tubes arranged with wide and narrow spaces called alleys, between them, the wide alley being used to remove defective tubes. The narrow 30 alley only would preferably be used for the reinforcing. Certain embodiments of the invention are shown in the accompanying drawings, wherein:

Figure 1 is a vertical section through a 35 water tube boiler constructed in accordance with my invention. Fig. 1^a is a detail of one of the baffles. And Figs. 2 and 3 are vertical sections through modifications.

Referring to Fig. 1, the numbers 1, 2 and 40 3 indicate the upper drums of the boiler and 4 is the lower drum, such drums being connected by the three banks of tubes 5, 6 and 7. The upper drums are connected by the usual sets of tubes 8 and 9. The boiler may be provided with the usual hand fired grates or with 45 automatic stokers, with gas, oil or powdered coal burners, the invention not being limited as to this detail of construction. Following the usual practice, the side 10 of the construction on which the gases of combustion 50 enter the tubes will be referred to as the front side and the other side (left) on which the outlet flue 11 is located will be referred to as the rear side, the banks or sets of tubes and 55 drums being correspondingly designated. Combustion takes place in the lower part of the furnace whose upper part 10 lies between the front wall 12 and the front tube bank 7. The flow of the gases of combustion across the 60 banks or sets of water tubes 7, 6, 5 is governed and directed by a pair of baffles arranged in part as described in Patent No. 1,614,948 issued to Alfred C. Danks, which in part is modified so as to constitute an important feature of my invention. The rear baffle is made

up of two sections, the upper section 13 extending downwardly from the rear drum 1, between the tubes in the rear tube bank 5, for a portion of their length and thence (part 14) in a direction transversely to said tubes across the tubes in the middle bank 6. 70

The front baffle is made up of three sections, the upper 15 passing transversely across the upper part of the middle tube bank 6 and the intervening space to the front tube bank 7. It may then follow the back of the rear tube of this bank downwardly or enter the tube bank any desired distance and follow any tube downwardly, as shown at 16, a convenient distance, and then turn to the rear 80 17 and cross the space between the first and second tube banks and the lower part of the middle, and if desired, the rear bank in a downwardly sloping direction, passing over the lower drum. 85

Between the upper rear drum 1 and middle drum 2 is shown the suspended baffle 18 for the protection of the drums, and particularly the drum splices 20, with an extension baffle 21 following the drum 1 and passing between and surrounding the upper ends of the tubes in the bank 5 to a junction with the rear baffle 13. This baffle is provided with any suitable form of reinforcing 18^a, as indicated by the dotted lines in Fig. 1^a, and may be suspended by rods 23 from the tubes 8. A similar baffle 22 may be suspended between the middle and front drums 2 and 3 so as to protect the splices 20 on these drums. As the circulation in the boiler is such that there is always water in these drums further protection is unnecessary. The construction, being independent of all tube support, the latter are left uncovered for heat absorption, may be readily inspected and on occasion, removed. Other advantages incident to the construction which may vary in details to suit other makes of boilers, will be readily apparent to those skilled in the art. 100

Fig. 2 shows only enough of the upper portion of the construction to illustrate a modified baffle 18^a between the drums 1 and 2 with supporting rods 23^a. The tubes 24 of the Fig. 1 construction are not used here so that the modified form of baffle 18^a as shown 110 may be used.

In the Fig. 3 construction, water circulating tubes 25, not present in Fig. 1 construction, are used, the baffle 18^b supported by the hangers 23^b being similar to the baffle and hangers of the Fig. 1 construction. 120

What I claim is:

1. In combination in a boiler of the vertical type having lower and upper drums and a plurality of sets or banks of tubes extending between the upper and lower drums and including a front bank and a second bank adjacent thereto, a firebox beneath the boiler, an outlet flue or stack at the rear of the boiler, a substantially flat baffle extending trans-

versely across the top of the lower drum in proximity thereto and upwardly inclined into the front bank of tubes above said lower drum, and an extension of the upper end of 5 said baffle extending longitudinally of said front bank of tubes, and then transversely of such tubes and across the second bank of tubes.

2. In combination in a boiler of the vertical type having lower and upper drums and 10 a plurality of sets of tubes extending between the upper and lower drums, and including front, middle and rear banks, a firebox beneath the boiler, an outlet flue or stack 15 at the rear of the boiler, a substantially flat inclined baffle extending transversely across the top of the lower drum through the middle bank of tubes and tangential to the lower drum, then longitudinally of the tubes of the 20 front bank, and finally across the tubes of the middle bank.

3. In combination in a boiler of the vertical bent tube type having a lower drum and three spaced upper drums and three sets or banks 25 of water tubes extending upward from the lower drum to the upper drums, a furnace beneath the boiler, an outlet flue or stack at the rear of the boiler, a baffle extending downwardly from the rear upper drum, longitudinally along the tubes of the rear bank for a 30 portion of their length and then transversely to such tubes and across the middle bank of tubes and a second baffle extending downwardly from a point between the upper portions 35 of the middle and rear tube banks across the middle bank of tubes to the first bank of tubes, thence downwardly parallel to said tubes a portion of their length and thence to the rear and downwardly over the top of the 40 lower drum tangentially thereof.

4. In a boiler of the vertical tube type having a lower drum and a plurality of upper drums with a plurality of banks of tubes between the upper and lower drums, cross baffling between the upper and lower drums, a 45 baffle lying in the rear bank of tubes and extending downwardly from the rear upper drum and then forwardly into the next bank of tubes, and a baffle section of reinforced 50 plastic material hardened in place suspended from above and extending between the rear upper drum and the drum next to it, and another baffle section of reinforced plastic material hardened in place secured at one end to 55 said baffle section and following the curvature of the lower side of the rear upper drum and extending into the tubes to a point where it engages and is supported by the upper end of the baffle in the rear bank of tubes.

5. In testimony whereof, I have hereunto subscribed my name this sixteenth day of February, 1928.

KINGSLEY L. MARTIN.
